BIRD CAGE

Alan Vincent Hinton, Brooklyn, N. Y.

Application May 9, 1956, Serial No. 41,415

Term of patent 14 years

(Cl. D31—2)

FIG. I

Des. 179,850

PAGE 2

FIG. 2

Des. 179,850

PAGE 3

FIG. 3

FIG. 5

FIG. 4

Fig. 1 is a front elevational view of a bird cage showing my new design;

Fig. 2 is a rear elevation thereof;

Fig. 3 is a plan view of Fig. 1;

Fig. 4 is a side elevation taken from the left of Fig. 1; and

Fig. 5 is a side elevation taken from the right of Fig. 1.

I claim:

The ornamental design for a bird cage, as shown.
